UNITED STATES PATENT OFFICE

OTTO HOLTKAMP, OF BERLIN, GERMANY

TABLE FOR INVALIDS' BEDS

Original application filed June 1, 1927, Serial No. 195,823, and in Germany June 10, 1926. Divided and this application filed April 10, 1928. Serial No. 268,969.

Tables used for invalids' beds are mostly adjustable as regards height by means of a slot and pin connection and adjustable for setting the inclination by means of a locked 5 arc. For adjustment the loosening and tightening of screws on both sides is necessary, which the invalid can seldom do for himself so that the adjustment is relatively bothersome.

10 The present invention has for its object to so set the position of tables on invalids' beds that the invalid, in so far as he is generally only able to use his hands, can effect the adjustment of his table, as regards height and 15 inclination, for himself by a simple operation. This is attained in that the table and its supports are connected to the bedstead or to a separate member attached thereto in a guiding slot and is fixable with removable pins 20 in notches, and further that the table itself is inclinably adjustable on its supports by means of spring catches released by pressure knobs. Separate screws for effecting the adjustment have therefore at no place to 25 be loosened and tightened again. One constructional form of carrying out the present invention is illustrated by way of example in the accompanying drawings, in which

Figure 1 shows a side view of a bedstead 30 with a table attached,

Figure 2 shows the connection between the table and its supports,

Figure 2a is a vertical longitudinal sectional view on the line 2a—2a of Fig. 2,

35 Figure 3 shows the trestle for fastening to the bedstead and the guides therein for the table supports.

The table top z is guided by means of its supports w on each side of the bed. Each 40 support engages with a pin w' in an inclined slot v' of a trestle v . There are two trestles v , each of which is attached to the bed frame or any part of the bedstead a and has, for example, two rests v'' and v^3 open to the same 45 side so that the supports w can be adjusted with the pins w'' fixed to the supports w in the rests v'' or v^3 , for the purpose of putting the table away in the position shown in dot-and-dash lines in Fig. 1 or for fixing in a 50 lower position as shown in the dotted lines,

whereby the pins w'' engage the rests v^3 , or in a higher position, as in full lines, whereby the pins w'' engage the rests v'' . The pins w' of the supports w have the necessary play in the slots v' of the trestles v so that the supports w with the pin w'' secured thereon may be lifted out of the rest v^3 and can be inserted in the rest v'' .

The inclination of the table is so adjustable that the table top z is connected to the 60 supports w by means of brackets y . To the supports w , flat springs x are attached bearing a knob x' engaging outwardly through the supports w and engaging with a pin x'' in one of the notches y' in the bracket y . By 65 pressing knobs x' inwardly the pins x'' come out of the notches y' and the table cover can be turned to the desired inclination and then fixed, as after releasing the knob x' the pin x'' falls back into the desired notch y .

70 The number of notches in the member y can naturally be made as many as desired in order to obtain any desired height.

I claim:

75 In a table for invalids' beds, in combination, two trestles each attached to one side of the bed, each trestle having an inclined longitudinal slot, supports for the table having pivots engaging in said slots, rests on said trestles open to one side of said slots, and 80 pins on said supports adapted to be engaged with said rests, substantially as described.

85 In testimony whereof I affix my signature.
